(57) **CLAIM**

The ornamental design for a self-checkout station, as shown and described.

DESCRIPTION

FIG. 1 is a perspective view of a self-checkout station showing our new design;

FIG. 2 is a front view of thereof;

FIG. 3 is a top view of thereof;

FIG. 4 is a right side view thereof; and,

FIG. 5 is a left side view thereof.

The broken lines illustrate portions of the self-checkout station and form no part of the claimed design.

1 Claim, 5 Drawing Sheets
